PORTABLE REVERSIBLE SCREEN
CONSTRUCTION

John T. Heck, Elmhurst, and Leo J. Du Mais,
Chicago, Ill., assignors to Da-Lite Screen Com-
pany, Inc., Chicago, Ill., a corporation of Illi-
nois

Application August 23, 1943, Serial No. 499,594

10 Claims. (Cl. 160—24)

The present invention relates to an improved portable screen, and is more particularly directed to a collapsible type of structure wherein the screen web is carried upon a suitable reel within a case that is detachably mounted on the structure to expose either surface of the screen web for use.

The structure supporting the screen web is provided with a collapsible tripod of the inverted type so as to bring its supporting legs substantially parallel with the surface on which they rest, which enables the case to be positioned very low on the structure.

As this type of screen is in demand for background purposes, it is important that it should extend as close to the ground-line as possible, and also that it be adjustable to various heights to expose predetermined lengths of screen web.

The reversible feature makes it possible to expose opposite surfaces of the screen web, as for instance, they may be of different colors, have scenic views for photographic purposes, or the screen web may have different finishes on each surface on which pictures may be projected.

It is an object of the present invention to provide a collapsible structure that is simple and strong in construction, light in weight, easily operated to open and collapse, and adjustable to various predetermined heights.

A further object is the provision of a screen structure having a detachable case provided with a screen web carried on a suitable reel therein whereby either surface of the screen web may be selectively exposed.

Another object is the provision of a screen structure having a collapsible tripod of the inverted type for supporting the structure close to the surface on which the tripod is positioned.

A further object is the provision of a slidable mounting on the structure and with means on the mounting whereby the screen case may be detachably supported and retained for pivotal movements on the mounting during the setting-up or collapsing of the structure.

Other and further objects will become apparent from the ensuing description and claims.

Referring to the drawings;

Figure 1 is a view in side elevation of the structure embodying our invention, the parts being shown in collapsed position for portable purposes.

Figure 2 is a face view partially broken away showing the screen in open position for use.

Figure 3 is an enlarged detail partial side elevation with some of the parts broken away to show the operative structure.

Figure 4 is an enlarged partial detail side elevation, showing the case in reversed position.

Figure 5 is a view taken substantially on the line 5—5 of Figure 4.

Figure 6 is an enlarged detail sectional view taken on the line 6—6 of Figure 5.

Figure 7 is an enlarged perspective view of the centerband showing the case attaching studs thereon.

Figure 8 is an enlarged partial detail view in side elevation showing a modified form of fastening means for the case on the structure; and

Figure 9 is an enlarged detail perspective view of the centerband construction employed in the modified form showing the slot openings therein.

The structure shown in the drawings is designed more particularly as a portable reversible screen construction for use as a background screen or as a screen on which pictures may be projected.

20 The screen and structure are combined in a unit which, when not in use, can be collapsed to a relatively small size and in suitable form to be easily carried about, and which can be easily and readily set up for use. When set up, the case may be bodily removed and replaced on the structure to expose the selected surface of the screen web forwardly of the structure.

The structure is designated as a whole as 10, and comprises a standard 11 which is preferably

30 hollow and has a supporting tripod 12 secured at 13 to the lower end of the standard 11. The tripod 12 is of the inverted type which permits its legs 14 when opened, to lie substantially parallel to the surface on which they rest. The legs 14 are pivoted at 15 to a fitting 16 fixed at 13 to the standard 11, and substantially intermediate their

35 lengths, the legs 14 have a connecting arm 17 pivoted thereto at 18 and with the upper ends of the arms pivoted at 19 to a fitting 20 slidably mounted on the standard 11. This fitting 20 has a spring lock 21 (Fig. 2) secured therein and the plunger 22 of the lock is adapted to be brought into alignment with and to enter the opening 23 provided in the standard 11, when the tripod is in open position.

45 The standard 11 is provided at its upper end portion with a cap 24 that may be of suitable design, but which as shown, fits into the tubular standard and is secured in position by a spring lock 25 threaded therein at 25a and which has a plunger 26 that extends into the standard to engage an extension rod 27.

50 The extension rod 27 which is preferably square in cross-section, is guided through a square opening 24a provided in the cap 24, and the lower

end of the rod 27 has a rider 28 fixed thereto for guiding the rod within the tubular standard 11. Spaced an appreciable distance from the rider 28, the rod 27 has a stop screw 29 secured therein which is adapted to engage the cap 24 to limit the extreme upward movement of the rod out of the standard. At predetermined positions, the rod 27 is provided with stop openings 30 which receive the plunger 24a of the spring lock 24 and retain the rod in fixed adjusted positions in the standard 11. The upper end of the rod is formed at a right-angle to provide a forwardly directed projection 31 to which the free end of the screen web is attached, and depending from this projection is a short stud 32 which engages the cap on the screen case, as will be later described.

The standard 11 has a mounting 33 positioned thereon and free to slide the entire length thereof between the cap 24 and the top fitting 20 of the tripod. The mounting 33 is provided on its forward face 34 with a vertically disposed slot 35 which terminates into an enlarged opening 36 at its lower end and into a larger opening 37 at its upper end. The slot 35 and openings 36 and 37 serve as means for detachably securing the screen case 38 to the mounting.

The case 38 is provided intermediate its length with a centerband 39 (Fig. 7) which has oppositely outwardly directed bosses 40—40 to each of which an outwardly directed stud 41 is secured. The studs 41 are each provided with a flattened sided shank 42 and an enlarged head 43 which cooperate with the slot 35 and openings 36 and 37.

The case 38 is attached to the mounting 33 by holding the case in a vertical position parallel with the standard 11 and with one of the studs 41 aligned with the enlarged opening 37 which permits the head 43 to enter therein and the flattened shank 42 to slide downwardly in the vertical slot 35 into the opening 36. At this position, the case may be pivotally turned and its weight will retain it in the opening 36. When the case is turned to horizontal position (Fig. 2) the flattened shank 42 will be positioned transversely of the slot 35 (Fig. 5) to prevent the accidental removal of the case, as for instance, when the screen web is extended and attached to the projection 31 (Fig. 3).

On each end of the case 38 is a cap 44 secured thereto by means of screws 45 and these caps serve as pivotal centers for a spring restorable reel 46 which has a suitable length of screen web 47 mounted thereon with its inner edge secured at 48 to the reel. The case has a longitudinally extending slot opening 49 therein through which the free end 47a of the web extends and which web is provided with a transversely extending slat 50 which has a slat-pull or attaching means 50b secured centrally thereof for attachment to the projection 31 of the extension rod 27.

In positioning or removing the case 38 from the mounting 33, it is only necessary to turn the case vertically and raise it bodily a slight distance. The turning movement of the case aligns the flattened shank 42 of the stud 41 with the slot 35 and permits it to be moved upwardly into the opening 37 (Fig. 5) which is large enough to permit of the passage of the stud head 43 therethrough. To facilitate the removal or positioning of the case on the mounting 33, the forward face 34 thereof is formed outwardly and downwardly at about centrally of the opening 37 which provides an off-set 34a which is just sufficient to align the shank 42 of the stud with the slot 35

while the head of the stud is slidably resting on the forward face 34 of the mounting.

Referring more particularly to Figs. 3 and 4, it will be noted the case is illustrated as being mounted in reversed position, that is, to expose different surfaces forwardly of the standard 11. When the case is mounted as shown in Fig. 3, the screen web is unwound rearwardly of its reel 46 while, as shown in Fig. 4, the screen is unwound forwardly of its reel and in order to maintain perfect vertical alignment of the screen web, two positions, namely 51 and 52 are provided in the projection 31 of rod 27. The position 51 is engaged by the slat-pull or attaching means 50b when the web is unwound from the inside of the reel, and position 52 is engaged when the web is unwound from the outside of the reel.

Figures 8 and 9 illustrate a centerband with a modified form of attachment for the case onto the mounting. In this instance, the case 38a has a centerband 39a which is provided with a pair of diametrically opposed slot openings 53 which are axially aligned and oppositely directed. Each of the slots 53 terminates into an enlarged opening 54.

In this construction, the stud 55 is provided with a flattened shank 56 which is permanently secured to the mounting 33a and when the case 38a is held vertically and is positioned on the mounting, the slot 53 will slide on the flattened shank 56 of the stud 55 until the enlarged opening 54 engages the shank, and at which time, the case may be turned to lock the same on the stud.

In either of the forms illustrated, the case may be removed and bodily turned to present either surface of the screen web forwardly of the standard.

To collapse the structure for portable purposes, the screen web is released from the projection 31 of the extension and spring restored in the case, which is then turned to vertical position parallel with the standard. Then the plunger 26 of the spring lock 25 at the top of the standard is actuated to release the extension rod 27 which is then free to drop into the standard 11, and the depending stud 32 on the projection 31 of the rod will enter an opening 57 in the case cap 44 to lock the case parallel with the standard and against turning movements. The tripod 12 is then collapsed by releasing the plunger 22 of the spring lock 21 which permits the fitting 20 to slide upwardly on the standard 11 and carry the arms 17 to collapse the legs 14 parallel with the standard.

The spring lock 58 is of the same construction as spring lock 25, and is secured in the mounting 33 with its plunger 59 spring-urged into openings 60 provided in the standard 11. These openings 60 are arranged at predetermined distances apart to lock the mounting 33 with the case 38 at different positions on the standard.

It is obvious that changes may be made in the construction, operation and arrangement of the parts without departing from the spirit of the invention, and we contemplate all such changes as fall within the scope of the appended claims.

We claim:

1. In a portable reversible screen construction, the combination of a standard having supporting legs therefor, an extension telescoped with said standard for adjustment of the height thereof, means for locking said extension in adjusted positions on the standard; a mounting slidably carried on the standard, a case having a screen

web and reel therein, means for locking said mounting in adjusted positions on the standard, and means on said mounting and on opposite sides of the case coacting to pivotally and removably support the case on the mounting, said means on opposite sides of the case facilitating the reversal of the case on the mounting to expose either surface of the screen web forwardly on the standard.

2. In a portable reversible screen construction, the combination of a support having a standard secured thereto, an extension telescoped with the standard for adjustment of the height thereof, means for locking said extension in adjusted positions on said standard, a case having a screen web and reel therein, a mounting slidably carried on the standard, means for locking said mounting in adjusted positions on the standard, and means on said mounting and case to pivotally support the case on said mounting, said last-mentioned means facilitating the removal of the case from the mounting to selectively position the case to expose either surface of screen web.

3. A collapsible stand construction comprising, a tubular standard having a support therefor, an extension, telescopic into said standard to raise and lower the height thereof, means for locking said extension at various heights on the standard, a mounting slidably carried on the standard, a case having a screen web and reel therein and being removably carried on the mounting, means for locking said mounting at different heights on the standard, said case having means on opposite sides thereof for attachment to said mounting to selectively expose either surface of screen web, and means on said extension for holding the free end of the screen web unwound from the reel.

4. A collapsible stand construction comprising, a tubular upright having supporting legs therefor, a member telescoping into said upright to raise and lower the height thereof, means for locking said telescoping member at various heights on said upright, a mounting slidably carried on said upright, a case having a screen web and reel therein and being detachably pivoted on said mounting, means for locking the mounting at different heights on the upright, and means associated with said telescoping member to which the web is adapted to be attached for maintaining a predetermined length of web unwound from the reel to selectively expose either surface of the screen web forwardly of the upright.

5. A screen stand structure for supporting a length of screen web to expose either surface thereof forwardly of the stand structure, comprising, a support, a mounting slidably carried on the support including means for locking said mounting at predetermined position on the support, a case housing the screen web and having means thereon to removably attach the case to said mounting, said last-mentioned means comprising interlocking members on the case and mounting aligned to attach and remove the case when the same is in vertical position and for locking the case against accidental removal when turned to horizontal position.

6. In a portable reversible screen construction, the combination of a standard having support-

ing legs therefor, a screen web and reel therefor, an extension telescoped with said standard for adjustment of the height thereof, means for locking said extension in adjusted positions on

5 the standard, a mounting for said reel slidably carried on the standard, said reel removable and reversible on said mounting, means for locking said mounting in adjusted positions on the standard, and means on said extension to which

10 the web is adapted to be connected for maintaining a predetermined length of web unwound from the reel to selectively expose either surface of the screen web forwardly of the standard.

7. In a portable reversible screen construction, the combination of a standard having supporting legs therefor, an extension telescoped with the standard for adjustment of the height thereof, a screen web and reel including a mounting therefor slidable on the standard, means for

15 locking said extension in adjusted positions on said standard, means for locking the mounting in adjusted positions on the standard, said reel being removably and reversibly attached to said mounting, said reel being also turnable into vertical position parallel with the standard, and means on the reel cooperating with said extension for locking the reel in parallel relation with the standard.

8. A collapsible screen stand construction comprising, a tubular standard having supporting legs therefor, an extension telescopic into said standard to raise and lower the height thereof, means for locking said extension at various heights on the standard, a case having a screen

35 web and reel therein, a mounting including pivotal means for the reel and slidable on the standard, said reel being removably and reversibly attached to said mounting, means for locking said mounting at different heights on the standard,

40 and means on said extension for holding the free end of the web unwound from the reel and maintaining the web in parallel relation with the standard and extension while either surface of the web is exposed for use.

9. A collapsible stand construction comprising, an upright having an extension telescoped therewith to raise and lower the height thereof, a projection at the upper end of said extension, a mounting slidably carried on said

50 upright, a case having a screen web and reel therein and being detachably and reversibly pivoted on said mounting, and means on said projection for attaching the free end of the screen web with the screen in parallel relation to the upright when either surface of the screen is exposed for use.

10. A portable reversible screen construction, comprising, a standard having supporting legs therefor, a screen web and reel, a mounting for said reel slidable on said standard, an extension for the standard for raising and lowering the height thereof, means on the extension for holding the free end of the screen web unwound from the reel, and pivotal means between

55 said reel and mounting cooperating to removably attach the reel on the mounting to selectively expose either side of the screen web for use.
